(57) **CLAIM**

The ornamental design for a joystick for game, as shown and described.

DESCRIPTION

FIG. 1 is a front elevational view of a joystick for game showing my new design of which the two components are combined together;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front elevational view of a first component of my new design, shown separately for ease of illustration;

FIG. 8 is a rear elevational view thereof;

FIG. 9 is a left side view thereof;

FIG. 10 is a right side view thereof;

FIG. 11 is a top plan view thereof;

FIG. 12 is a bottom plan view thereof;

FIG. 13 is a front elevational view of a second component of my new design, shown separately for ease of illustration;

FIG. 14 is a rear elevational view thereof;

FIG. 15 is a left side view thereof;

FIG. 16 is a right side view thereof;

FIG. 17 is a top plan view thereof; and,

FIG. 18 is a bottom plan view thereof.
